UNITED STATES PATENT OFFICE.

CHARLES J. GUSTAFSON AND FRANK C. MOCK, OF CHICAGO, ILLINOIS, ASSIGNEES TO
STROMBERG MOTOR DEVICES COMPANY, OF CHICAGO, ILLINOIS, A CORPORATION
OF ILLINOIS.

CARBURETOR.

Application filed November 12, 1917. Serial No. 201,447.

Our invention relates to carburetors.

The modern internal combustion engine usually operates over a wide range of speeds and consequently requires corresponding quantities of explosive mixture.

Carburetors as heretofore constructed have lacked essentially in ability to increase or expand their capacity to provide mixture in accordance with the increase demanded by the engine. Our invention provides the carburetor with means to permit it to expand its capacity for delivery of both gasoline and air when the engine demands the same. We provide in addition to the main air inlet an auxiliary inlet which is normally closed. This inlet, when the demand calls for it, provides an additional supply of air and controls the amount of fuel supplied to the fuel jet or jets so that as the air supplying capacity is increased, the gasoline supplying capacity is increased in proper proportion.

The construction which we provide gives straight discharge from the jet to the outlet of the carburetor and controlled by the throttle, and any gasoline which condenses on the walls drains back to the point of highest air velocity where it will be picked up again. The drainage is so steep that there is no opportunity for gasoline to collect in pockets. The gasoline is delivered at all times into the point of highest air velocity. When an additional air supply for high speed is admitted it comes in the form of an annular sheath or tube, tending to prevent the mixture from condensing on the walls and developing into liquid streams.

Another feature of our additional air controlling valve is the fact that it operates like a second Venturi tube around the primary Venturi tube thus permitting it to bring in its supply of air at high velocity and to pick up any gasoline which drains down along the walls. At the same time the pressures are all nicely balanced so that an even annular discharge of air is created. There is no tendency for the valve to become jammed or cocked by the air pressure.

We further provide improved means operated by the air valve to supply additional fuel in proper proportion with the additional air allowed to pass by the valve.

In the accompanying drawings which form a part of the present specification, 55

Figure 1 is a front elevation of a device embodying our invention;

Figure 2 is a vertical axial section taken on line 2-2 of Figure 1;

Figure 3 is a front elevational view with 60 the carburetor body in vertical diametral section, and

Figure 4 is a vertical diametral sectional view showing the construction and operation of the additional fuel supply well. 65

As shown, the carburetor comprises a main barrel 1 generally cylindrical in outline, having a cap member 2 forming an outlet from the interior of the barrel and having a primary air inlet 3 at the lower end of the barrel at substantially right angles to the axis of the same. A constant level chamber 4 of the usual construction is provided and has the fuel supply inlet 7. 70

The cap member 2 has an outlet opening 8 therethrough, this opening being controlled by a throttle valve 9 mounted on a rocking shaft 10 controllable by the operator for governing the speed of the motor. A suitable flange 11 is provided around the outlet 8 for attaching the carburetor to the intake of the engine. 75

The air valve 17 mounted on the rotary shaft 18 controls the air inlet 3. The shaft 18 is connected to a suitable control preferably mounted on the dashboard of the vehicle and used for starting or other special purposes. The bottom of the main casing 1 is closed off except for the inlet 3. A jet member 19 is arranged substantially axially 80 in the casing 1 having a tip or nozzle 21 extending above the fuel level which is indicated by the dotted line 22. This nozzle 21 extends upward into the Venturi tube 23 so that its upper end projects above the most restricted portion of the Venturi tube. The venturi 23 is mounted axially in the shell 1 upon the wall 24 which divides the lower portion of the casing 1 from the upper portion thereof. 90

The casing 1 has the opening 25 in the side walls thereof for admitting air in addition to the air which enters the primary inlet 3, when the demand of the engine necessitates such a supply. 95

The Venturi tube 23 is held in place in

the collar 27 by means of the set screw 26 shown in Figure 2.

The cylindrical body 1 is provided at its upper end with a cylindrical bore concentric with the jet and the venturi and in this bore the valve body 30 is slidably mounted. The valve body 30 has a reduced central portion 31 of slightly greater diameter than the Venturi tube. A circular tapered wall 32 joins the reduced portion 31 with a bearing portion 33 which is guided in the bore of the cylinder 1. The tapered wall 32 is adapted to rest upon the top of the venturi 23 to close off the interior of the hollow 15 valve from the auxiliary air inlet 25.

At the upper end of the reduced portion 31 the walls of the valve member flare out to provide a bearing portion 34 for guiding the valve within the bore of the cylinder 1.

20 The manner in which the opening of the auxiliary valve 30 controls the gasoline supply to the nozzle 21 will now be set out. The barrel 1 is provided with an extension 50 within which is found a well 51, the 25 bottom of which is in communication by way of passageway 52 with a passageway 53 communicating with the interior of the float chamber. A port 54 below the passageway 53 communicates with the well 57 30 in the fuel jet at 19 by way of the passage 56. The valve rod 55, having a pointed or needle end 58, controls the port 54 to govern the passage of liquid fuel from the float chamber to the jet.

35 The valve stem 55 is connected by means of the bracket 59 which projects through a slot 61 in the side wall of the barrel 1. For steadyng the valve 30 against the fluctuation, the piston 120 is provided and is 40 secured to the valve stem 55 in the well 51. As this well is filled with liquid fuel, resistance is offered by the piston 120 to any sudden changes of movement on the part of the valve 30. As will presently be explained, this piston also serves to lift additional fuel to be discharged into the carbureting passageway of the carburetor.

45 The valve stem 55 is inserted into a sleeve 121 having its spherical head 66 fitting into a corresponding seat in the bracket. A 50 spring spider 122 attached to the sleeve 121 holds the same in place and permits the valve stem 55 and piston 120 to align properly. The valve stem 55 passes down 55 through an opening 131 in the plug 123 which fits in the top of the well 51. A transverse passageway 124 connected through the nipple 125 has an outlet 126 in the venturi 23 above the most restricted portion 60 of the same, forming a secondary fuel jet. The opening 131 normally permits air to enter the passageways 124-126. The piston 120 and the passageways 124-126 are 65 provided as a means for supplying fuel to the mixing chamber upon opening of the

annular valve 30. This is also particularly valuable for accelerating purposes after the valve 30 has started to open, or is about to open. When the suction within the carburetor is suddenly increased by throwing 70 the throttle valve open, the valve 30 will be drawn upward and at the same time a small quantity of fuel will be raised by the plunger 120 through the opening 123 and this fuel flows through passageway 124 to 75 and from the outlet 126. Air entering at the opening 131 is drawn in with the fuel in proper proportion. The employment of the well 51 on the float chamber side of the restriction prevents the leaking of air into 80 the passageway through the jet. In this embodiment an absolutely clear open passageway is secured above the nozzle 21. The upper end of the stem 55 is provided with a knob 67 for turning the stem on the 85 threaded portion to adjust the needle valve with respect to the port 54. A spring latch 68 mounted on the head 66 engages the knob 67 and prevents accidental turning. The needle valve 58 is so proportioned that when the air valve 30 opens communication 90 between the float chamber and the normal well 57 will be correspondingly increased to provide an additional amount of fuel for the additional amount of air drawn into the 95 mixing chamber.

The connection between the butterfly valve 17 in the intake 3 and the body of the valve 30 is provided by the compound connecting rod 110 which comprises the upper 100 rod 111 having a head 112 sliding loosely in the hole in the outer wall of the valve 30. This rod projects down into the sleeve 113 and has a head 114 at its lower end, between which head and the flange 115 of the sleeve 105 is placed a compression spring 116. The sleeve 113 is slotted at its lower end, as shown at 117, and is provided with a transverse rod or pin 118 which is adapted to be engaged by the structure 119 fastened 110 upon the butterfly valve 17. By means of this connection, the valve body 30 is held down on its seat, that is, on top of the venturi 23 when the valve 17 is closed for starting purposes.

115 The jet 19 comprises a hollow cylindrical block substantially axial of the venturi and of the cylindrical chamber 1. At its lower end this hollow cylindrical jet is screw threaded. A screw plug 69 closes 120 the bottom of the same. A perforated hollow sleeve 70 having an enlarged head 71 at the bottom thereof, is inserted into the bottom of the jet and divides the interior 125 of the same into two wells, namely, the normal well 57 and the accelerating well 72. These two wells are connected together by four small openings 73 through the enlarged head 71. A nozzle 74 fits snugly within the head 71 and projects into the hollow 130

sleeve 70 and through the upper end 75 of the same, terminating in a reduced opening 76 which discharges into the space 77 below the tip or nozzle 21. An annular space 78 is left between the nozzle 74 and the hollow sleeve 70, this annular space opening into the space 77 below the tip 21 through two small ports 79.

The side walls of the hollow sleeve member 70 are pierced by a number of holes which provide communication between the annular space 78 and the well 72. These holes are formed of different sizes, the uppermost one 80 being relatively small and the lowermost one 81 being relatively large. The purpose of these transverse holes and the openings 79 is to provide an air bleed on higher engine speeds and to preserve the accelerating character of the well 72.

20 The operation is as follows: Assuming that the float chamber is properly supplied with liquid fuel, preferably gasoline, and that the level of the same stands on substantially the dotted line 22 shown in Figure 3, 25 when it is desired to start the engine, the butterfly valve 17 is closed by the dash control device. Movement of the valve 17 to the closed position puts the spring 116 under tension sufficient to hold the valve 30 down 30 upon the venturi 23 thereby preventing opening of said valve during starting. The throttle is partially opened and the engine is turned over.

When the throttle 9 is opened wide and 35 the engine is at high speed, the suction demand is unsatisfied by the air entering the venturi 23, and the suction will raise the annular valve 30, permitting the entry of air through opening 25 in an annular sheath 40 around the outer edges of the venturi 23 into the main carbureting chamber and through the outlet to the intake of the engine. This movement of the valve 30 is opposed by the spring 116 and is steadied by 45 the plunger 120.

As the annular valve 30 rises it carries upward with it the gasoline controlling valve 55-58 permitting an increase of flow of fuel through the restriction 54.

50 When the air valve 30 is open it holds the fuel controlling valve 58 open so that more gasoline is available to be drawn in, in accordance with the increased flow of air.

The taper of the valve 58 is such as to 55 open the restriction in accordance with the opening of the air valve 30. It is clear that so long as the increase of air is accompanied by a corresponding properly proportioned increase of fuel, the proper mixture will be maintained.

We do not intend to be limited to the precise details shown and described, the appended claims defining the scope of our invention.

60 65 We claim:—

1. In a carburetor, the combination of a carbureting chamber having an air inlet and a mixture outlet, an air valve responsive to suction in said carbureting chamber, a constant level fuel supply chamber, fuel supply 70 means comprising a well fed from said constant level supply chamber, a fuel port communicating with the upper part of said well above said constant level and opening into said carbureting chamber, an air vent connected with and establishing a path of air flow through said fuel port for normally preventing the creation of a fuel feeding suction in said well, and a fuel raising piston in said well adapted to be operated by the opening of said air valve for mechanically moving fuel up to a level where it will be drawn into said fuel port.

2. In a carburetor, the combination of a carbureting chamber having an air inlet and a mixture outlet, a constant level supply chamber, a fuel well communicating therewith, a fuel port opening from the upper part of said fuel well into said carbureting chamber, an air vent from which air flows through said fuel port for controlling the suction effective in said fuel well, a movable member in said well, and means having operative connection with said movable member whereby to cause movement of the latter to raise fuel in said well for discharge through said fuel port when the suction within the carbureting chamber is suddenly increased.

3. In a carburetor, the combination of a carbureting chamber having an air inlet and a mixture outlet, a throttle in said mixture outlet, a constant level supply chamber, a main fuel jet fed therefrom and discharging into said carbureting chamber, auxiliary fuel supply means comprising a fuel well fed from said constant level chamber, a fuel port opening from above the normal fuel level in said well into said carbureting chamber, an air vent feeding air through said fuel port for controlling the suction effective in said fuel well, a piston in said well, and means having operative connection with said piston whereby to cause movement of the latter to raise fuel in said well for discharge through said fuel port when the suction within the carbureting chamber is suddenly increased by the opening of said throttle valve.

4. In a carburetor, the combination of a carbureting chamber, a restriction in the chamber, an annular air valve slideable in said carbureting chamber and having its seat on the top of said restriction, a fuel well on one side of said carbureting chamber, a fuel supply chamber communicating with said well, a fuel passageway above the fuel level between said well and said carbureting chamber, said passageway being open to atmosphere to the top of said well, a bracket 120 125 130

on said annular valve, a stem secured to said bracket, and a plunger on said stem disposed in said fuel well for raising the fuel to said fuel passageway.

5. In a carburetor, the combination of a barrel member, a venturi in the barrel, an annular air valve slidable in said barrel and having its seat on the top of the venturi, an open valve well on one side of said barrel, 10 said valve well having a seat in the lower part thereof, a bracket on the annular air valve projecting through a slot in the barrel, an adjustable valve stem secured to said bracket, said stem having a valve cooperating 15 with the valve seat, a fuel supply chamber communicating with the well above said valve seat, a plunger on said stem, a passageway above the fuel level between said venturi and the upper end of the well, said 20 passageway being open to atmosphere through the top of the well.
6. In a carburetor, the combination of a carbureting chamber having an air inlet and a mixture outlet, an auxiliary air valve with- 25 in said carbureting chamber responsive to the suction in said chamber, a constant level

fuel supply chamber, an auxiliary well fed from said fuel supply chamber, a fuel port leading from the upper part of said auxiliary well above the normal level therein and 30 to said carbureting chamber, an air vent adapted to normally admit a sufficient supply of air into said fuel port to prevent the suction in said carbureting chamber from drawing fuel from said well through said 35 port, said air vent being connected with said auxiliary air valve, and a fuel raising piston in said well connected with said auxiliary air valve, said auxiliary air valve being responsive to increased suction in the carbureting chamber to raise said piston to lift fuel from said well into said fuel port and to move said air vent to increase the amount of airflow through said port in proportion with the amount of fuel delivered to said 40 port from said well.

In witness whereof, we hereunto subscribe our names, this 10th day of November, A. D. 1917.

CHAS. J. GUSTAFSON.
FRANK C. MOCK.
